UNITED STATES PATENT OFFICE

AARON SYLVESTER, OF INDIANAPOLIS, INDIANA.

FENDER.

1,114,936.

Specification of Letters Patent.

Patented Oct. 27, 1914.

Application filed April 16, 1914. Serial No. 832,278.

To all whom it may concern:

Be it known that I, AARON SYLVESTER, a citizen of the United States, residing at Indianapolis, in the county of Marion and State of Indiana, have invented certain new and useful Improvements in Fenders, and I do hereby declare the following to be a full, clear, and exact description of the invention, such as will enable others skilled in the art to which it appertains to make and use the same.

This invention relates to a fender especially adapted for use on automobiles and motor trucks, although it is not necessarily limited to such use.

An object of this invention is the provision of a fender pivotally movable on a vertical axis adapted to deflect a person or object struck thereby laterally and out of the path of the vehicle.

Another object is to provide suitable supporting means permitting the fender to be raised out of operative position.

With these and other objects in view, the invention consists in the novel construction, arrangement and formation of parts as will be hereinafter specifically described, claimed and illustrated in the accompanying drawing, in which,

Figure 1 represents a side elevation of the fender applied to use. Fig. 2 represents a vertical transverse sectional view therethrough. Fig. 3 represents a top plan view of the fender applied to use. Fig. 4 represents a bottom plan view of the pivoted bearing plate for the fender, and, Fig. 5 represents a fragmentary view of the top of the fender.

Referring to the drawing in detail where-in similar reference numerals designate corresponding parts throughout the several views, the numeral 6 indicates the attaching and supporting member for the fender, the rear ends of which are adapted to be secured forwardly of the motor truck or automobile. Ears 7 are formed in the supporting member 6 and receive the apertured ears 8 of the bearing plate 9 these latter ears being pivotally secured to the ears 7 by suitable pins 10. Extensions 11 are formed on the supporting member 6 below the ears 7 thereof and provide a rest for the bearing plate 9 for supporting the latter in operative horizontal position.

A pivot bolt 12 is positioned through the bearing plate 9 and through the rear portion

of the fender 13 which is arranged over the bearing plate 9. Suitable friction reducing rollers 14 are secured to the top face of the fender 13 and are adapted to travel upon an annular boss 15 formed on the under side of the bearing plate 9. The fender 13 is preferably of adequate width to extend from one side wheel 16 of the vehicle to the opposite side wheel thereof, and the front edge of said fender is preferably curved and covered with a suitable pneumatic or other cushioning means 17.

Springs 18 are arranged on opposite sides of the pivot bolt 12 of the fender and connect the latter with the supporting member 6, whereby the fender is normally and resiliently retained in operative position. Rollers 19 are journaled in suitable brackets 20 adjacent the front edge of fender 13 and are adapted to contact the surface of the wheels 16 when the fender is turned, as when coming in contact with an object or person.

From the foregoing it is apparent that I have provided a fender of such construction that an object or person, when struck thereby, will actuate the fender to turn it upon its pivot 12 and throw or deflect such person or object laterally of the path of the vehicle and to a safe distance from the wheels thereof. The springs 18 automatically return the fender to normal position after an operation thereof, and the fender may be moved to vertical position upon the pivot pins or bolts 10 when the vehicle is not in operation.

What I claim is:

1. The combination with a vehicle having a bracket secured thereto, of a segmental fender having pivotal movement, both horizontal and vertical, about said bracket, cushioning means secured to the front edge of said fender and wheel contacting rollers located adjacent the front rim of said fender.

2. The combination with a vehicle having a bracket secured thereto of a bearing plate pivoted to said bracket on a horizontal axis, a segmental fender pivotally mounted on said bearing plate on a vertical axis, cushioning means secured to the forward edge of said fender and wheel contacting members located adjacent the ends of said forward edge.

3. The combination with a vehicle having a bracket secured thereto, of a bearing plate pivoted to said bracket on a horizontal axis, a segmental fender pivotally mounted on

said bearing plate on a vertical axis, cushioning means secured to the forward edge of said fender, wheel contacting members located adjacent the ends of said forward edge 5 and resilient means normally holding said fender away from the wheels.

4. The combination with a vehicle having a support secured thereto, of a bearing plate 10 hingedly connected to said support on a horizontal axis, a raised boss formed in the center of said bearing plate, a segmental fender vertically pivoted to said bearing plate at the center of said boss, anti-friction rollers secured to said fender and adapted to op-

erate on said boss, cushioning means positioned along the outer edge of said fender, wheel contacting rollers carried by said fender and resilient means interposed between said support and said fender on both sides of said pivot for normally holding said 20 fender away from the wheels.

In testimony whereof I have signed my name to this specification in the presence of two subscribing witnesses.

AARON SYLVESTER.
